NONFREEZING HYDRANT

John H. Schmid, Erie, Pa., assignor to J. A. Zurn
Manufacturing Company, Erie, Pa., a corpora-
tion of Pennsylvania

Application September 20, 1946, Serial No. 698,268

6 Claims. (Cl. 137—13)

1

This invention relates generally to hydrants and more particularly to hydrants of the non-freezing type.

Conventional hydrants of the anti-freeze type utilize various means of draining water from the column leading to the spout at or near the base of the column. These hydrants require a porous filling at the base of the hydrant, thereby requiring the valve in the hydrant to be located a greater distance below the surface of the ground. Conventional hydrants of the anti-freeze type have the valve located below the frost line. This valve is connected by a suitable pipe or other conduit means with the surface outlet and utilizes various means of draining water from the conduit at or near the valve in the base when the hydrant valve is closed. In these prior devices there has been siphonage of waste water and subsurface seepage water through the water column when a reduced pressure or vacuum occurred in the water column or in the hydrant supply line.

It is, accordingly, an object of my invention to overcome the above and other defects in non-freezing hydrants, and it is more particularly an object of my invention to provide a non-freezing hydrant which is simple in construction, easy to install, economical in manufacture, economical in cost, and efficient in operation.

Another object of my invention is to provide a non-freezing hydrant which requires no drain or other connections to the outside thereof, thereby eliminating any chance of cross-connection between a sewer line and a supply line.

Another object of my invention is to provide novel means of mounting the water column of a non-freezing hydrant a sufficient distance below the ground to prevent freezing.

Another object of my invention is to provide a novel connecting means between the hose connection and an anti-freezing hydrant.

Other objects of my invention will become evident from the following detailed description, taken in conjunction with the accompanying drawings, in which:

Fig. 1 is a vertical sectional view illustrating an embodiment of my novel non-freezing hydrant;

Fig. 2 is a side elevational fragmentary view showing the operating lever for the valve of my novel non-freezing hydrant; and

Fig. 3 is a fragmentary vertical sectional view of the novel connection for the end of the hose combined with my novel non-freezing hydrant.

Referring now to the drawings, Figs. 1, 2, and 3 show a base plate 1 having a depending flange

2

portion 2 for receiving a valve sleeve 3 and a depending flange portion 4 for receiving a vertically extending sleeve 5. The base plate 1 is preferably disposed substantially at the ground surface. The valve sleeve 3 has a threaded portion 6 on the lower end thereof and threadably engages the internally threaded hub portion 7 of fitting 8. Fitting 8 has vertically disposed apertures 9 and 10 in axial alignment with the sleeve 3 and a branch line 11 having a threaded hub portion 12 for receiving the lower threaded end 13 of sleeve 5. The upper end of the sleeve 3 is threaded at 14 for receiving an internally threaded flanged cap member 15 having a centrally disposed aperture 16 for journaling a valve rod 17 which extends axially of the sleeve 3 downwardly therethrough. The lower end of the rod 17 is engaged to a valve stem 18 by means of a sleeve 19 and pins 20. Cylindrically shaped members 22 having intermediate sealing washers 23 are disposed on the valve stem 18 between a collar 24 and a nut 25 engaging threaded portion 26 of stem 18. The washer 23 seals the aperture 9 in the fitting 8 and prevents passage of water therethrough. The lower end of the stem 18 has a seating member 28 disposed between collar 29 on stem 18 and a nut 30 threadably engaging the lower threaded end of the stem 18. The seating member 28 seats on seating portion 32 of the fitting 8 and seals the aperture 10 in fitting 8 to the passage of water from a supply line 33. A spring member 35 surrounding the rod 17 is disposed on the upper end of the rod 17 between cap member 15 and a collar 36 attached to the rod 17 by a pin 37. The cap member 15 and the collar 36 have recesses 38 and 39 for nesting the ends of the spring member 35. A cam lever 40, shown more particularly in Fig. 2, has bifurcated end 41 which is attached to the upper end of the rod 17 by a pin 42. The bottom surface 43 of the cam lever 40 engages the cap member 15, and is a predetermined distance from the horizontally extending pin 42 so that the seating member 28 seats on the seating surface 32 of the fitting 8 to prevent the flow of water from the supply line 33 when the bottom surface 43 of the cam lever 40 is in engagement with the cap member 15. When the cam lever 40 is moved in either direction, a distance 90 degrees, one side surface 44 of the bifurcated end 41 of the cam lever 40 engages the top of the cap member 15. Inasmuch as the surface 44 of the bifurcated end 41 of the cam lever 40 is a greater distance from the pin 42 than the bottom surface 43 of the bifurcated end 41 of the cam lever 40, the seating

member 28 moves away from the seating surface 32 of the fitting 8 and permits the passage of supply water through the aperture 10 of the fitting 8.

The upper end of the sleeve 5 is threaded at 50 to receive a cap member 51 having a threaded portion 52 for threadably engaging the threaded portion 50 of the sleeve 5, a groove 53 for receiving a U-shaped washer 54, and opposed locking portions 73 on the upper side thereof. A cylindrical connecting member 60 is adapted to extend into sleeve 5 and has a threaded flange member 61 with aperture 62 threadably engaged to the bottom threaded portion of the connecting member 60. A ball check member 63 seats on the seating surface 64 of the aperture 62 to check the flow of water from the connecting portion 60. Web member 65 is disposed in the connecting portion 60 to restrain the movement of the ball member 63. The connecting member 60 is connected to any suitable fitting and has outwardly extending locking pins 66 for locking engagement with the locking portions 73 on the flange 51. It will be evident from the foregoing description that I have provided a very simple anti-freezing hydrant in which there is no opportunity for any siphonage to take place or any opportunity for a cross-connection between water supply line and sewer or ground water.

A suitable protective cap member (not shown) may be provided for the connecting member 60 when it is removed from the sleeve 5.

In operation, the connecting member 60 is projected into the sleeve 5 and a locking connection is made between the locking jaws 73 and the locking pin 66 of the connecting member 60. The handle or lever 40 is then pushed downwardly 90 degrees, thereby unseating the seating member 28 to permit the flow of water from the supply line 33. The water from the supply line 33, being of comparatively higher pressure pushes the ball 63 away from the seat 64 of the aperture 62 in the flange 61, thereby permitting the flow of water through the connecting member 60 to any suitable hose connection. When it is desired to shut off the flow of water, the lever 40 is raised to an upright position as shown in Fig. 1 to seat the seating member 28 on seat 32 of the fitting 8 and the connecting member 60 is removed from the sleeve 5 with the ball member 63 automatically engaging the seat 64 of the aperture 62 of the threaded flange member 61.

I provide a cover member 70 of semi-spherical shape with a handle 71 hinged at 72 on the base member 1 to cover up the lever 40 and the sleeve 5.

Various changes may be made in the specific embodiment of my invention without departing from the spirit thereof or from the scope of the appended claims.

What I claim is:

1. A non-freezing hydrant comprising a fitting having an inlet for connection to a fluid supply conduit and an outlet, a valve disposed in said fitting adapted to be disposed below the frost line of the earth, means adapted to extend above the earth's surface to operate said valve, a female connecting sleeve attached to the outlet of said fitting and adapted to extend to the surface of the earth, a male outlet conduit having a connecting portion adapted to be removably telescoped within said female sleeve and in communication with the outlet of said fitting and a check valve in the bottom of said male outlet

conduit for checking the flow of fluid therefrom toward said valve.

2. A non-freezing hydrant comprising a fitting adapted to be disposed below the frost line of the earth having an inlet for connection to a fluid supply conduit, an outlet, and a valve seat disposed between said inlet and said outlet, a valve seating member adapted to sealingly engage said seat of said fitting to control the flow of fluid between said inlet and said outlet, means for operating said seating member, a female connecting sleeve attached to the outlet of said fitting and adapted to extend upwardly therefrom to the surface of the earth, a removable male outlet conduit having a connecting portion adapted to be telescopically disposed in said sleeve and a check valve in the bottom of said male conduit member adapted to check the flow of fluid therefrom toward said valve.

3. A non-freezing hydrant comprising a fitting adapted to be disposed below the frost line of the earth having a seating surface and an inlet and an outlet, said seating surface being between said inlet and said outlet, a seating member engaging said seating surface to control the flow of fluid between said inlet and said outlet, a rod for attachment to said seating member, means for reciprocating said rod, an upwardly extending, open sleeve attached to the outlet of said fitting and adapted to extend to the earth's surface, a male outlet conduit having a removable connecting portion adapted to be telescopically disposed in said open sleeve whereby fluid may flow therethrough and a check valve in the bottom of the connecting portion of said outlet conduit for sealing the flow of fluid therefrom toward said valve.

4. A non-freezing hydrant as set forth in claim 3 wherein a base member for disposal on the surface of the earth is provided with two apertured portions for receiving said rod and said sleeve and a cover is hingedly disposed on said base member.

5. A non-freezing hydrant comprising a fitting having an inlet for connection to a fluid conduit and an outlet, a valve associated with said fitting adapted to be disposed below the frost line of the earth for controlling the flow of fluid through said fitting, means for operating said valve, an upwardly extending, open female connecting sleeve attached to the outlet of said fitting, a male outlet conduit adapted to be removably telescopically disposed in said open sleeve whereby fluid may flow therethrough upon the opening of said valve, and a check valve in the lower end of said male outlet conduit adapted to prevent the flow of fluid from said conduit toward said valve.

6. A non-freezing hydrant as set forth in claim 5 wherein means are provided for locking and sealingly engaging said outlet conduit and said female sleeve.
